UNITED STATES PATENT OFFICE.

HENRY J. PAIN, OF 121 WALWORTH ROAD, COUNTY OF SURREY, ENGLAND.

SIGNAL-TORCH.

SPECIFICATION forming part of Letters Patent No. 319,843, dated June 9, 1885.

Application filed August 7, 1884. (No model.)

To all whom it may concern:

Be it known that I, HENRY J. PAIN, a subject of the Queen of Great Britain, residing at 121 Walworth Road, in the county of Surrey, England, have invented new and useful Improvements in Signal-Torches, of which the following is a specification.

This invention relates to torches especially for signaling purposes, and it consists in a cylindrical casing combined with a cylindrical torch having a fuse at one end, and having a shoulder intermediate of the ends, whereby the torch may rest on one end of the casing in reverse positions. One end of the cylindrical casing is provided with a fuse-igniting surface, which is protected by a cap, as herein-after more fully set forth.

This invention is illustrated in the accompanying drawings, in which Figure 1 is a side view, partly in section, showing the position of the torch when not in use. Fig. 2 is a similar view showing the position of the torch when in use.

Similar letters indicate corresponding parts. The letter A designates the casing, and B the torch, both substantially cylindrical and one fitted to the other.

C indicates the fuse at one end of the torch, and D the shoulder intermediate of the ends thereof.

E denotes the fuse-igniting surface of the casing, and F the cap for protecting such surface.

The torch B is filled with a combustible material suitable for signaling purposes, which takes fire from the fuse C when the latter is ignited. When the torch B has been lighted, it may be inserted into the casing A from the lower end, as shown in Fig. 2, to convert the casing into a handle for sustaining the torch in the proper position, while during transpor-

tation and at other times when the torch is not in use it may be reversed and inserted into the casing from the upper end, as shown in Fig. 1, to protect the fuse. The shoulder D 45 serves to support the torch on the upper open end of the casing A in either position, and in order to bring the greater part of the torch above the casing when it is in use, the shoulder is preferably located nearest to the lower end 50 of the torch.

The igniting-surface E of the casing consists of a coating applied to the lower end of the casing, where it is closed, of a material suitable to ignite the fuse C by friction, reference being had to the nature of the fuse, and the protecting-cap F is simply fitted on the casing at such end, to be taken off when the igniting-surface is to be used.

What I claim as new, and desire to secure 60 by Letters Patent, is—

1. The combination of the cylindrical casing with the reversible cylindrical torch having the fuse at one end and the shoulder intermediate of the ends for supporting the torch 65 in reverse positions on one end of the casing, substantially as shown and described.

2. The cylindrical casing having one end provided with a fuse-igniting surface and the protecting-cap fitted on such end of the casing, in combination with the cylindrical torch having the fuse at one end and the shoulder intermediate of the ends, substantially as 70 shown and described, for the purpose set forth.

In testimony whereof I have hereunto set my hand and seal in the presence of two subscribing witnesses.

HENRY J. PAIN. [L. S.]
